VENTILATOR UNIT

Ronald J. Weber and Wesley J. Higgins, Wausau, Wis.,
assignors to Wausau Metals Corporation, Wausau, Wis.

Filed Jan. 12, 1973, Ser. No. 322,932

Term of patent 14 years

Int. Cl. D23—04

U.S. Cl. D23—151

Fig. 1

Fig. 2

Fig. 3

Fig. 4

Fig. 5

FIG. 1 is a front elevation view of a ventilator unit embodying our new design,

FIG. 2 is an isometric view of our ventilator unit in its closed position, showing the front and bottom facing surfaces,

FIG. 3 is an isometric view of our ventilator unit in its open position, showing the front and bottom facing surfaces,

FIG. 4 is an isometric view of our ventilator unit in its open position, showing top and front facing surfaces,

FIG. 5 is a rear elevation view of our ventilator unit.

The window frame members are shown in broken lines in FIGS. 1, 2, 3 and 4 for illustrative purposes only.

We claim:

The ornamental design for a ventilator unit, as shown and described.
